(57) CLAIM

I claim the ornamental design for an off-shelf bracket, as shown and described.

DESCRIPTION

FIG. 1 is a perspective view of a first embodiment of an off-shelf bracket showing my new design;

FIG. 2 is a top plan view thereof;

FIG. 3 is a front elevational view thereof;

FIG. 4 is a left side elevational view thereof;

FIG. 5 is a bottom plan view thereof;

FIG. 6 is a rear elevational view thereof;

FIG. 7 is a right side elevational view thereof;

FIG. 8 is a perspective view of a second embodiment of an off-shelf bracket showing my new design; and,
FIG. 9 is a perspective view thereof, shown without environmental structure.

The broken lines shown in the drawings are for illustrative purposes only and form no part of the claimed design.
